The ornamental design for the saw horse bracket, as shown and described.

DESCRIPTION

FIG. 1 is a front elevational view of the saw horse bracket showing my new design;

FIG. 2 is a rear elevational view thereof;

FIG. 3 is a left side elevational view thereof;

FIG. 4 is a right side elevational view thereof;

FIG. 5 is a top plan view thereof; and,

FIG. 6 is a bottom plan view thereof.

The broken line showing of a portion of a saw horse in FIGS. 1 and 3 is for illustrative purposes only and forms no part of the claimed design.

FIG. 1

FIG. 2

FIG. 3

FIG. 4

*FIG. 5**FIG. 6*
